UNITED STATES PATENT OFFICE.

WILLIAM BAYLEY, OF SPRINGFIELD, OHIO.

DESIGN FOR A TOBACCO-CUTTER.

SPECIFICATION forming part of **Design No. 26,355**, dated December 1, 1896.

Application filed August 17, 1896. Serial No. 603,090. Term of patent 7 years.

To all whom it may concern:

Be it known that I, WILLIAM BAYLEY, a citizen of the United States, residing at Springfield, in the county of Clark and State of Ohio, have invented and produced a new and original Design for Tobacco-Cutters, of which the following is a specification, reference being had to the accompanying drawing, forming a part hereof.

10 The drawing consists of a perspective view, which is deemed sufficient to fully illustrate my design.

The leading feature of my design consists in a base formed of the shape and substantially the size of a plug of tobacco and ornamented by painting or otherwise, so as to resemble as closely as possible the appearance of said plug of tobacco, the other feature of the design being in effect a battle-ax mounted

20 upon the base in such a manner as to appear

to have been partially driven into the base by a blow.

In the drawing, *a* represents the base, which is rectangular in shape and of a size and ornamentation to resemble a plug of tobacco. 25

b is the blade or battle-ax, which is curved at each side, but formed straight where it joins the base, so as to give the appearance of having been driven into the base, with the handle *a'* substantially parallel with said 30 base.

What I claim is—

The design for a tobacco-cutter, substantially as herein shown and described.

In testimony whereof I have hereunto set 35 my hand this 11th day of August, A. D. 1896.

WILLIAM BAYLEY.
